UNITED STATES PATENT OFFICE.

FREDERICK S. DUESENBERG, OF INDIANAPOLIS, INDIANA.

CRANK SHAFT FOR INTERNAL-COMBUSTION ENGINES.

Original application filed February 11, 1921, Serial No. 444,082. Divided and this application filed
March 5, 1923. Serial No. 622,785.

This invention relates to a novel and improved crank-shaft for eight-cylinder internal combustion engines, the aim being to secure an engine characterized by light weight, economy in the use of fuel, simplicity of construction, and accessibility.

The invention will be best understood by reference to the following description, when taken in connection with the accompanying drawings of one illustrative embodiment thereof, while its scope will be more particularly pointed out in the appended claims.

In the drawings:

Fig. 1 is a vertical, longitudinal, sectional view of an internal combustion engine provided with a crank-shaft exemplifying my invention; and

Fig. 2 is a somewhat conventionalized perspective view of the crank-shaft, with the so-called crank-pin "collars" and their counterbalances omitted.

Referring to the drawings, and to the embodiment of the invention which is selected for exemplification, and having reference first to Fig. 1, there is shown an internal combustion engine having eight cylinders A, which for convenience of description will be referred to as A¹ to A⁸, inclusive, because of the fact that it is customary in the art to refer to the cylinder at the front of the engine as the No. 1 cylinder, and to the second as the No. 2, and so on. The cylinders are formed as a single casting, or to use a common expression in the art, they are cast in a block. The cylinders are disposed with their axes in a single plane, herein vertical,—that is to say, the cylinders are upright and in a single row, as distinguished from V-type engines. Working in the cylinders are pistons B, connected by connecting rods C to crank-pins D of a crank-shaft of novel construction, which is housed in a crank-case 9. For convenience of description, the several pistons, connecting rods and crank-pins will be referred to by the letters B, C, and D, accompanied by the numerals corresponding to the cylinders. In the present example, the latter are provided with a removable cylinder head 10 presenting combustion chambers for the several cylinders. The admission of the combustible mixture to the chambers, the ignition thereof, and the release of the exhaust gases, may be effected by any usual valve mechanism and ignition apparatus, which,

however, need not be described herein, since it forms no necessary part of the present invention.

The crank-shaft is mounted in three bearings, namely: two end bearings 11 and 12, and an intermediate bearing 13, usually called a center bearing. The use of this number of bearings makes it possible to build a very short, light engine, as short in fact as the average six-cylinder engine, and even shorter than others. This is advantageous for several reasons, among them being the resultant light weight of the entire engine, a desirable compactness of the same, and the fact that the crank-shaft, being short, is not subject to the distortion and whipping action, with the accompanying vibration, which has heretofore characterized eight-cylinder engines in which the cylinders are disposed in a single row.

The crank-shaft which is of novel form will now be described, reference being had particularly to Fig. 2. The crank-shaft is provided with two end bearing portions 14 and 15, and an intermediate or center bearing portion 16 mounted in the bearings 11, 12 and 13, respectively. The crank-shaft may be considered as being made up of two similar units or groups of crank-pins, each comprising four pins whose axes are in a plane perpendicular to the plane of the axes of the pins of the other group. Thus the axes of the crank-pins D¹, D², D³ and D⁴, will lie in a plane perpendicular to the plane containing the axes of the crank-pins D⁵, D⁶, D⁷ and D⁸. One of these groups is disposed between the front and intermediate bearing, and the other between the latter and the rear bearing.

It should here be observed that in each group there are two contiguous crank-pins whose axes are in alignment and in the same radial plane,—or to state it differently, one of these crank-pins may be regarded as an axial prolongation of the other. This applies to the crank-pins D² and D³ of one group, and to the crank-pins D⁶ and D⁷ of the other.

The crank-shaft comprises four short crank-arms 17, 18, 19 and 20, and four long crank-arms 21, 22, 23 and 24. Each of the short crank-arms connects the crank-pin to a main bearing portion, while each of the long crank-arms extends across the main axis of the crank-shaft and directly connects one

crank-pin to another, without the interposition of a main bearing portion.

Preferably, the crank-shaft is suitably counterweighted. In the case of the short crank-arms 17, 18, 19 and 20, there are provided counterweights 25, 26, 27 and 28, the weight of each of which is substantially equal to the weight of its corresponding crank-arm, not including the crank-pin. It should here be observed that the crank-pin D¹ is in balance with the crank-pin D², and that the crank-pin D⁴ is in balance with the crank-pin D³. Likewise, in the other group, the crank-pin D⁵ is in balance with the crank-pin D⁶, and the crank-pin D⁸ is in balance with the crank-pin D⁷. This does not take into account the two masses of metal, one intermediate the crank-pins D² and D³, and the other intermediate the crank-pins D⁶ and D⁷. These are counterbalanced by weights 29 and 30, which are formed on long arms 31 and 32, respectively, each extending from its pair of crank-pins across the main axis of the crank-shaft.

Thus it is evident that by this simple and convenient arrangement of the bearings, crank-pins and counterweights, there is provided a crank-shaft which can easily be placed in static and running balance. Preferably, the thickness of the crank cheeks and the diameters of the main bearings increase from the front toward the rear end of the crank-shaft,—that is to say, the thickness of the crank-arm 18 is greater than that of the crank-arm 17, and the thickness of the crank-arm 20 is greater than that of the crank-arm 19, while the diameter of the main bearing portion 16 is greater than that of the main bearing portion 14, and in turn the diameter of the main bearing portion 15 is greater than that of the main bearing portion 16. This is helpful in avoiding torsional vibration in the crank-shaft. In practice, it is found that an engine embodying the described construction operates with such a minimum of vibration that it is capable of running at speeds far in excess of any other type of which I am aware, and thus an engine of high power and low weight is produced.

This application is a division of my pending application, Ser. No. 444,082, filed February 11, 1921.

Having thus described one embodiment of

my invention, but without limiting myself thereto, what I claim and desire by Letters Patent to secure is:

1. A crank-shaft having eight crank-pins arranged in two groups of four, a plane containing the axes of the crank-pins of one group being perpendicular to a plane containing the axes of the crank-pins of the other group, and three main bearing portions only, one at each end and one intermediate said groups, the thickness of the crank cheeks increasing from one end of the crank-shaft toward the other.

2. A crank-shaft having eight crank-pins arranged in two groups of four, a plane containing the axes of the crank-pins of one group being perpendicular to a plane containing the axes of the crank-pins of the other group, and three main bearing portions only, one at each end and one intermediate said groups, the diameters of the main bearing portions increasing from one end of the crank-shaft toward the other.

3. A crank-shaft having eight crank-pins arranged in two groups of four, a plane containing the axes of the crank-pins of one group being perpendicular to a plane containing the axes of the crank-pins of the other group, and three main bearing portions only, one at each end and one intermediate said groups, the thickness of the crank-cheeks increasing from one end of the crank-shaft toward the other, and the diameters of the main bearing portions increasing from one end of the crank-shaft toward the other.

4. A crank-shaft having eight crank-pins arranged in two groups of four, a plane containing the axes of the crank-pins of one group being perpendicular to a plane containing the axes of the crank-pins of the other group, and three main bearing portions only, one at each end and one intermediate said groups, the thickness of crank-arms adjacent one end of the crank-shaft being greater than the thickness of crank-arms adjacent the other end, and the diameter of the main bearing portion at one end being greater than the diameter of the main bearing portion at the other end.

In testimony whereof, I have signed my name to this specification.

FREDERICK S. DUESENBERG.
